LOCKING GAS CAP

Mathew G. Ivandick, Waukegan, Ill.

Application November 22, 1933, Serial No. 699,165

3 Claims. (Cl. 70—90)

This invention appertains to closure caps for the filling necks of tanks, such as gasoline tanks utilized for supplying fuel to the internal combustion engines of automobiles.

5 One of the primary objects of my invention is to provide novel means for locking the closure cap on the filling neck, so that the same can only be removed by the proper person and thereby prevent the draining of the tank by unauthorized 10 persons.

Another salient object of my invention is the provision of a closure cap for the filling necks of gasoline tanks embodying a pin-tumbler lock having rotatable with the barrel thereof a locking 15 bar movable into and out of locking engagement with the cam flanges of the filling neck, the cap carrying depending lugs for fitting in the notches of the neck so as to prevent rotation of the cap, the engagement of the locking bar with 20 the cam flanges preventing the removal of the cap from the neck.

A further important object of my invention is the provision of novel means whereby the locking bar can be brought into and out of alinement with 25 the lugs on the cap, whereby the locking bar can be introduced with the lugs into the notches of the neck and thereafter rotated under the cam flanges of the neck by the barrel of the lock to prevent unauthorized removal of the cap.

30 A further object of my invention is the provision of a locking cap for the filling necks of gasoline tanks, which is so constructed that the cap can be utilized with ordinary necks of tanks without any additions or changes to the necks.

35 A further object of my invention is the provision of novel means for resiliently associating the lock bar with the barrel of the cap and the body of the cap, whereby the lock bar can be conveniently moved under the cam flanges and act as 40 means for drawing the cap and the gasket carried thereby into sealing engagement with the neck, whereby loss of gasoline between the neck and cap is prevented and whereby slight variations in the height of the cam flanges will be 45 taken care of.

A still further object of my invention is to provide a locking cap for the filling necks of gasoline tanks, which will be durable and efficient in use, one that will be simple and easy to manufacture 50 and one which can be placed upon the market at a reasonable cost.

With these and other objects in view, the invention consists in the novel construction, arrangement, and formation of parts, as will be 55 hereinafter more specifically described, claimed

and illustrated in the accompanying drawing, in which:

Figure 1 is a diametric section through my improved cap showing the same applied to a filling neck, the section being taken substantially on the line 1—1 of Figure 2 looking in the direction of the arrows. 5

Figure 2 is a horizontal section through the cap and neck taken substantially on the line 2—2 of Figure 1 looking in the direction of the arrows. 10

Figure 3 is a fragmentary section through the filling neck illustrating the locking position of the lock bar relative to the cam flanges of the neck.

Referring to the drawing in detail, wherein similar reference characters designate the corresponding parts throughout the several views, the letter A generally indicates my improved cap and B the neck of a tank with which the cap can be associated. 15

The filling neck B can be of the usual construction generally employed in connection with the gasoline storage tanks of automobiles and as shown, the same embodies the cylindrical neck portion 5 having the in-turned annular flange 6 on its upper edge, which is provided with diametrically disposed notches 7 and 8. The in-turned flange 6 carries depending arcuate locking cam flanges 9 which lie on opposite sides of the notches 7 and 8. As shown, the high points of the cam flanges are oppositely disposed relative to 20 one another. 25

My improved cap A can be constructed from any desired material and in any preferred manner and embodies a top wall 10 having a depending annular peripheral flange or skirt 11 for snugly engaging about the neck B. Formed on the axial center of the top wall 10 and depending therefrom is a boss 12 which is bored for the reception of the rotatable barrel 13 of a conventional pin-tumbler lock. This barrel 13 can be held against endwise movement within the cap in any preferred manner, such as by the use of a retaining plate 14 connected with the barrel and engaging the lower face of the boss 12. 35

Arranged in spaced relation to the skirt 11 are 40 diametrically disposed locking lugs or lips 15 which are adapted to detachably fit within the notches 7 and 8 of the neck B, when the cap is disposed on the neck, to prevent rotation of the cap relative to the neck. A sealing gasket 16 formed from cork or other compressible material is disposed 45 against the inner face of the top wall 10 and is held in position between the skirt 11 and the lugs 15. This gasket 16 is adapted to bear against the upper face of the neck when the cap is in position 50 55

thereon, so as to prevent loss of gasoline or other liquid contained in the tank between the cap and the filling neck.

Rotatable with the barrel 13 of the lock is a diametrically extending rigid locking bar 17. This locking bar is of such a length as to engage under the cam flanges 9 of the neck, when the barrel of the lock is rotated by the key to its locked position. My novel means of associating the locking bar with the barrel of the lock and the body of the cap forms an important part of my invention, as by this means I am enabled to provide in effect a floating lock bar, the advantages of which will be hereinafter more fully set forth.

15 As shown, the retaining plate 14 carries depending guide pins 18 and the hub 19 of the locking bar 17 is provided with openings for receiving the pins. This allows the locking bar to slide toward and away from the barrel of the lock and the pins form a guide thereof.

20 Formed integral with the opposite sides of the boss 12 are studs 20, which extend below the boss and these studs have fitted against the same a retaining disc 21 which is held in place by means of screws 22 which extend through the plate and into threaded bores formed in the studs. An expansion spring 23 is placed between the retaining disc 22 and the hub 19 of the locking bar and this spring normally functions to hold the locking bar 25 in a raised position. If desired, the hub 19 of the lock bar can have formed thereon a projection 24 which forms a seat for retaining the spring 23 in place. It is to be also noted that the lock bar is disposed between the studs 20 and thus, these 30 studs serve to limit the swinging movement of the lock bar.

In use of my improved closure cap, the key 25 for the lock is inserted in the barrel so as to release the barrel from the boss 12 for free rotation, 40 after which the barrel 13 is turned so as to align the arms of the lock bar with the locking lugs 15 casted on the cap. The cap is now inserted on the filling neck B and the lugs 15 and the lock bar 17 will ride into the notches 7 and 8. Upon 45 rotation of the barrel 13 by the key, the arms of the lock barrel will first engage under the low points of the cam flanges 9 and upon continued rotation of the barrel, the lock bar will gradually ride up the inclined faces of said flanges. When 50 the barrel has been turned to its locked position with the lock bar 17 disposed substantially at right angles to the locking lugs, the key is removed and manipulation of the lock is then prevented by unauthorized persons.

55 Obviously, the position of the lugs 15 within the notches 7 and 8 will prevent rotation of the cap. An outward pull on the cap is resisted by the engagement of the lock bar under the cam flanges 9. Thus, the removal of the cap other than by the person possessing the correct key is prevented.

60 By my means of mounting the lock bar 17 in position, the lock bar is permitted to give relative to the flanges 9 and variation in these flanges will be taken care of by the downward movement of the lock bar. Further, the continued upward thrust of the lock bar on the flanges tends to hold the cap tight down on the neck, allowing the gasket 17 to form a seal with the neck to prevent any 65 loss of liquid between the neck and the cap.

70 In order to further help the movement of the

lock bar under the cam flanges 9, the top face of the arms of the lock bar can be curved transversely, as clearly shown in Figures 1 and 3.

By my construction of the cap, the parts can be readily assembled and the entire cap can be manufactured at a low cost.

Obviously, when it is desired to remove the cap from the neck, the key is reinserted in the barrel and the barrel is again turned to align the arms of the locking bar with the notches of the neck, after which the cap can be pulled upward and off of the neck due to the fact that the arms of the lock bar and the lugs will all be in alignment with the notches of the neck.

Changes in details may be made without departing from the spirit or the scope of this invention, but what I claim as new is:

1. The combination with the filling neck of a tank having an in-turned flange provided with diametrically disposed notches and depending cam flanges arranged between the notches, of a removable closure cap for the neck including depending rigid locking lugs for engaging in said notches when the cap is disposed on the neck, an axially disposed boss having a bore formed on the cap, a lock including a barrel rotatably mounted in the boss, spaced depending pins carried by the inner end of the barrel of the lock, a lock bar having openings for slidably receiving the pins, studs formed on the boss extending below the boss, a retaining disc secured to the studs, and an expansion spring arranged between the lock bar and the retaining disc.

2. A closure cap for the filling necks of tanks comprising a body having a top wall and a depending skirt, diametrically disposed locking lugs formed on the body in spaced relation to the skirt, a gasket disposed against the inner face of the top wall and disposed between the skirt and the lugs, an axially disposed boss formed on the top wall having a bore, a key-operated lock including a barrel rotatably mounted in said bore, securing studs formed on the body and extending below the boss, a lock bar rotatable with the barrel into and out of alignment with the lugs including radially extending arms and a hub, the hub being provided with openings, depending pins connected with the barrel slidably received in said openings, a retaining disc, means securing the retaining disc to the studs and an expansion spring interposed between the retaining disc and the hub of the lock bar, the upper faces of the arms of the lock bar being curved transversely.

3. The combination with the filling neck of a tank having an in-turned flange provided with oppositely disposed notches and cam flanges lying on opposite sides of the notches; of a removable closure cap for the neck including a body having depending locking lugs for engaging in the notches to prevent rotation of the cap on the neck, a key-operated lock carried by the cap including a rotatable barrel, a diametrically extending lock bar, means slidably and non-rotatably connecting the lock bar with the barrel whereby the lock bar is freely rotatable with the barrel and movable toward and away from the barrel, a retaining member disposed below the bar, means securing the retaining member to the body, and an expansion spring disposed between the lock bar and the retaining member.

70 MATHEW G. IVANDICK.
